UNITED STATES PATENT OFFICE.

JULIAN F. DRAKE, OF TRACY, MINNESOTA.

DETACHABLE BOILER-FLUE.

SPECIFICATION forming part of Letters Patent No. 698,471, dated April 29, 1902.

Original application filed March 26, 1901, Serial No. 52,594. Divided and this application filed November 5, 1901. Serial No. 81,167. (No model.)

To all whom it may concern:

Be it known that I, JULIAN F. DRAKE, a citizen of the United States, residing at Tracy, in the county of Lyon and State of Minnesota, have invented certain new and useful Improvements in Detachable Boiler-Flues; and I do hereby declare the following to be a full, clear, and exact description of the invention, such as will enable others skilled in the art to which it appertains to make and use the same.

My present invention relates to detachable boiler-flues, and has for its object to improve the same in the several particulars hereinafter noted.

15 The invention consists of the novel devices and combinations of devices hereinafter described, and defined in the claims.

This application is in the nature of a division of my prior application for detachable boiler-flues, Serial No. 52,594, filed March 26, 1901.

25 The invention is illustrated in the accompanying drawing, wherein the single view shows a portion of the flue-sheet of a fire-box 25 and a flue connected thereto by one of my improved devices, some parts being shown in section and others in plan.

30 The numeral 1 indicates a flue-sheet, and the numeral 2 one of the flues. The flue-sheet 30 has flue seats or passages 3, which are somewhat larger than the exterior of the flue 2. These seats 3 are bored without taper—that is, are of the same diameter throughout.

35 The numeral 4 indicates an inwardly-tapered or slightly-conical sleeve, which is secured on the end of the flue 2 by threaded engagement therewith, as shown at 5. This sleeve 4 is advisably about one-sixteenth of an inch in thickness at its inner end and about 40 three-sixteenths at its outer end, although these dimensions may of course be varied. In its outer end said sleeve is preferably provided with several pin-seats 4', into which the pin of a pin-wrench may be inserted to tighten the 45 sleeve on the tube. A thin packing ring or collar 6, of copper or other relatively soft metal of high fusibility, is placed around the sleeve 4 and within the seat 3 of the flue-sheet. This collar is tapered to fit the exterior 50 of said sleeve, and in view of this taper when it is first tightly pressed between said collar and said seat 3 it will be engaged at its exterior surface only by the sharp outer edge of the flue-sheet, which is cut to form said seat

3. This engagement will indent the said collar and form an annular shoulder, although slight, around the said collar. This shoulder will prevent the collar from being slipped farther through the flue-sheet; but under increasing pressure, caused by screwing the 60 sleeve 5 farther inward on the flue, the said relatively soft ring 6 will be caused to fill up any irregularities in the seat 3. This feature is important, since the seats 3 after continued use become irregular, so that it would be difficult or impossible to form a steam-tight joint therewith by a hard metal, such as iron or steel or even brass.

At its other end—to wit, the end not shown—the flue may be secured to the other flue-sheet 70 by any suitable device—as, for instance, by the device claimed in my said prior application or by another device, such as that herein illustrated.

In some cases the tapered sleeve 5 may be 75 rigidly secured to the tube by brazing or otherwise; but this construction would not be the full equivalent of that employing the screw-threaded sleeve.

What I claim, and desire to secure by Letters Patent of the United States, is as follows:

1. In a boiler, the combination with a flue-sheet, of a flue having rigidly secured to one end an inwardly-tapering conical sleeve, and a packing ring or bushing of relatively soft 85 material, but of high fusibility, interposed and pressed between the said sleeve and its seat in the flue-sheet, which packing ring or bushing closely fits said conical sleeve and tapers in the same direction therewith, both 90 at its interior and exterior surface, substantially as described.

2. In a boiler, the combination with the flue-sheet 1 having the non-tapered seat 3, of the flue 2 having the inwardly-tapered conical 95 sleeve 5 screw-threaded thereon, and the tapered packing ring or bushing 6 of copper, pressed between said sleeve 5 and seat 3, said ring or bushing 6 closely fitting said sleeve and tapering in the same direction therewith, 100 both at its exterior and interior surface, substantially as described.

In testimony whereof I affix my signature in presence of two witnesses.

JULIAN F. DRAKE.
